Des. 207,758
Patented May 23, 1967

207,758

APPLIANCE FOR PREPARING FOOD AND THE LIKE

James R. Mecredy, Lakewood, Ohio, assignor to The Cleveland Range Company, Cleveland, Ohio, a corporation of Ohio

Filed Mar. 28, 1966, Ser. No. 1,650

Term of patent 14 years

(Cl. D81—10)

Fig. 1

Fig. 2

FIG. 1 is a front view of the appliance embodying my new design;

FIG. 2 is a top plan view of the appliance;

FIG. 3 is a side view of the appliance as viewed from the left hand side of FIG. 1; and

FIG. 4 is a side view looking from the right hand side of FIG. 1.

The dominant features of my design reside in the portions shown in full lines.

I claim:

The ornamental design for an appliance for preparing food and the like, as shown and described.
